FRUIT PACK

Philip M. Williams, Oakland, Maine, assignor, by
mesne assignments, to The Canal National
Bank of Portland, Portland, Maine, a national
banking association, and William B. Nulty,
Portland, Maine, as trustees

Application September 11, 1947, Serial No. 141,304

Term of patent 14 years

(Cl. D58—13)

To all whom it may concern:

Be it known that I, Philip M. Williams, a citizen of the United States, residing at Oakland, in the county of Kennebec, State of Maine, have invented a new, original, and ornamental Design for Fruit Pack, of which the following is a specification, reference being had to the accompanying drawing, forming part thereof.

Fig. 1 is a top plan view of a fruit pack showing my new design;

Fig. 2 is an edge view thereof; and

Fig. 3 is a fragmentary cross sectional view taken on line 3—3 of Fig. 1.

The design is characterized by the depressed rim formation intersected by the marginal pockets and the two cut-away corners.

I claim:

The ornamental design for a fruit pack, as shown and described.

PHILIP M. WILLIAMS.
